(57) **CLAIM**

The ornamental design for an integrated electronic limited slip rear wheel drive axle cover, as shown and described.

DESCRIPTION

FIG. 1 is a perspective view of an integrated electronic limited slip rear wheel drive axle cover showing the new design.

FIG. 2 is a front elevation view of the integrated electronic limited slip rear wheel drive axle cover.

FIG. 3 is a first side elevation view of the integrated electronic limited slip rear wheel drive axle cover.

FIG. 4 is a second side elevation view of integrated electronic limited slip rear wheel drive axle cover.

FIG. 5 is a top plan view of the integrated electronic limited slip rear wheel drive axle cover; and,

FIG. 6 is a bottom plan view of the integrated electronic limited slip rear wheel drive axle cover.

Any portion of the integrated electronic limited slip rear wheel drive axle cover configuration shown in broken lines is for the purpose of illustrating environmental structure and forms no part of the claimed design.
